Bridgeport, Conn., assignors to The Bridgeport Metal
Goods Manufacturing Company, Bridgeport, Conn., a corporation of Connecticut

Filed June 8, 1967, Ser. No. 7,408

Term of patent 14 years

(Cl. D48—24)

FIG. 1 is a top elevational view of a flashlight or similar article showing our new design;

FIG. 2 is a side elevational view thereof;

FIG. 3 is a bottom elevational view thereof;

FIG. 4 is a front elevational view thereof; and

FIG. 5 is a rear elevational view thereof.

The dominant features of our new design are shown in solid lines in the drawings and reside primarily in the flashlight body. The broken line showing of a lamp bulb in FIG. 4 is for illustrative purposes only.

We claim:

The ornamental design for a flashlight or similar article, substantially as shown and described.
